Specification for Design.

Patented Feb. 28, 1922.

Application filed June 6, 1921. Serial No. 475,448. Term of patent 14 years.

To all whom it may concern:

Be it known that I, LOUIS ROSENTHAL, a citizen of the United States of America, residing at Baltimore city, and State of Maryland, have invented a new, original, and ornamental Design for Pins, Brooches, and Rings, of which the following is a specification, reference being had to the accompanying drawing, forming part thereof.

In the drawing,

The figure is a plan view of a pin, brooch or ring before being formed, showing my new design.

I claim:

The ornamental design for pin, brooch, or ring, as shown.

LOUIS ROSENTHAL.
